(57) **CLAIM**

The ornamental design for a cylinder-type inflator for airbag module, as shown and described.

DESCRIPTION

FIG. 1 is a front elevational view of a first embodiment of a cylinder-type inflator for airbag module;
FIG. 2 is a rear elevational view thereof;
FIG. 3 is a top plan view thereof;
FIG. 4 is a bottom plan view thereof;
FIG. 5 is a right side elevational view thereof;
FIG. 6 is a left side elevational view thereof;
FIG. 7 is a top, front, and left side perspective view thereof;
FIG. 8 is a bottom, rear, and right side perspective view thereof;
FIG. 9 is a front elevational view of a second embodiment of a cylinder-type inflator for airbag module;
FIG. 10 is a rear elevational view thereof;
FIG. 11 is a top plan view thereof;
FIG. 12 is a bottom plan view thereof;
FIG. 13 is a right side elevational view thereof;
FIG. 14 is a left side elevational view thereof;
FIG. 15 is a top, front, and left side perspective view thereof;
FIG. 16 is a bottom, rear, and right side perspective view thereof;
FIG. 17 is a front elevational view of a third embodiment of a cylinder-type inflator for airbag module;
FIG. 18 is a rear elevational view thereof;
FIG. 19 is a top plan view thereof;
FIG. 20 is a bottom plan view thereof;
FIG. 21 is a right side elevational view thereof;
FIG. 22 is a left side elevational view thereof;
FIG. 23 is a top, front, and left side perspective view thereof; and,
FIG. 24 is a bottom, rear, and right side perspective view thereof.
The broken lines in the drawings depict environmental subject matter only and form no part of the claimed design.
